MECHANICAL MOVEMENT

Arthur E. De Koning, Portland, Oreg.

Application March 9, 1931, Serial No. 521,284

1. Claim. (CL 29—69)

My invention consists in means for guiding in parallel, or fixed angular relationship two planes in separative movement, and a certain embodiment of the device with cooperating members in a sawing machine.

The principal object of my invention is to provide reliable and durable means for accomplishing this effect adaptable for use as a means for projecting cutting tools through the work in determinate, rectilinear paths.

A second object is to provide such a guide means of comparatively great amplitude of operative movement in that space whose magnitude in the direction of such motion is no greater than the distance of separation of the stationary and projected planes.

A third and particular object of my invention is the provision of a sawing machine whose blade is capable of rectilinear movement in that plane containing it through a relatively great distance and whose dimension in the direction of movement of the saw blade is approximately equal only to the diameter of the saw blade when the same is retracted.

Other objects and advantages of my invention will be apparent in the following discourse wherein the significance of the reference characters in the accompanying drawing, details of construction and manner of operation of a typical machine embodying my invention and the particular advantages thereof are explained.

Figure 1 is a diagrammatic perspective representation of the essential effects of the device of my invention.

Figure 2 is a diagrammatic representation of the essential elements of the device.

Figure 3 represents a perspective view of a sawing machine in which my invention is embodied wherewith the saw-blade has been removed.

Figure 4 represents a top view of the sawing machine.

Figure 5 represents a side view of the locking device used to hold the saw in its retracted position together with fragmentary portions of supporting and cooperating parts.

Figure 6 is a diagram illustrative of certain proportions of the elements of the machine.

Figure 7 is a diagram illustrative of certain proportions of other elements cooperating with those illustrated in Figure 6.

The essential elements of the machine comprise two rigid links 1' and 2' (Figure 2) attached together and to the supporting and supported members 3' and 4' respectively, by three parallel shafts, or pivots 5', 6' and 7' respectively, and

two other rigid links 8' and 9' similarly connected together and to the supporting and supported members 3' and 4' respectively by three shafts, or pivots 10', 11', and 12' disposed perpendicularly to the pivots 5', 6', and 7'. The two extreme limits of movement of a cutting tool such as a circular saw mounted upon the supported member 4' are indicated by the circles in broken lines 13' and 14'; the path of motion of the saw is indicated by the straight line 15'. The positions of the several links and pivots when the saw occupies the position indicated by 13' are indicated by the broken lines as 16' while the path of the pivot 10' is indicated by the arc 17'.

The essential effects of this combination of links, pivots, and attachments therefor are illustrated in Figure 1. It is desired to guide the motion of a plane A in motion reciprocally in the direction of the line C—D normal thereto and to the fixed plane B coincidentally parallel with the plane A. A member revolving about the axis X'—X' would be constrained to motion parallel with the plane V normal thereto and perpendicular to the plane B in which lies the axis X'—X'. Likewise a member revolving about the axis Y'—Y' would be constrained to motion parallel with the plane H normal thereto and also perpendicular to the plane B in which lies the axis Y'—Y'. The only motion possible in a member pivotally mounted upon both the axes X'—X' and Y'—Y' would be along the line C—D coincident with the line of intersection of the two planes V and H. It is obvious that a single integral member mounted upon both axes would be fixed and immobile.

If, however, separate members are rotatably mounted upon these two axes and two similar members are mounted upon the axes X—X and Y—Y and those revolving about the X and X' axes are rotatably connected together by another axis parallel therewith, and those revolving about the Y and Y' axes are similarly connected together, a motion of the plane A, supported by such a system in the direction of the line C—D normal thereto would be possible. Thus the constraints of movements of members about two systems of angularly separated axes are combined to constrain motion in the line of intersection of the planes into which the two systems of members are constrained respectively.

A further effect is that the plane A, in relation to which the axes X—X and Y—Y are rigidly related, moves in the direction of the normal C—D precisely parallel with the plane B in rela-

tion to which the axes $X'-X'$ and $Y'-Y'$ are rigidly related.

While the most advantageous relationship of the angularly disposed systems of axes is the true perpendicular, it will be obvious that great variations from the perpendicular will not change the relative motion of the plane A with reference to the plane B. As for instance, the axes $X-X$ and $X'-X'$ may be disposed horizontally and the axes $Y-Y$ and $Y'-Y'$ may be disposed at only a slight angular separation of merely a few degrees. Parallelism of the axes in each system is the only critical requirement of these effects.

15 In the application of this principle variations in the precise form of the apparatus just described are necessitated by reason of the fact that practical construction does not admit of disposing the several elements as illustrated in 20 the diagram. Identical effects, however, are provided for by the means employed in the device of my invention distinguished by unequal link lengths and variant dispositions of the terminal axes of the link systems, the one complementary to the other, designed to provide for the folding of the mechanism into the smallest space. Particularly, the horizontal axis $11'$ is raised and shifted laterally and the link $8'$ is proportionately lengthened. The opposite axis $12'$ is lowered and the link $9'$ shortened.

30 The embodiment of these features in a machine for practical use is shown in the Figures 3 and 4. In Figure 3 it will be observed that the links 8 and 9 are of unequal length and the termini thereof are situated at different levels so that the axis 12 moves through a plane situated below the axis 11 . In Figure 4 it will be observed that both terminal axes of the link system composed of the links 1 and 2 are situated in the plane through which the axis at 7 moves. The link systems thus approach a common plane perpendicular to the line of motion of the tool-head 25 and hence fold into a very compact space.

40 An exaggerated degree of these relationships is illustrated in the Figures 6 and 7 wherein the link 1 is represented by $1''$, the link 2 by $2''$, the joint therebetween by $5''$, the terminal axes of links $1''$ and $2''$ by $6''$ and $7''$ respectively, the link 8 by $8''$ in Figure 7 the link 9 by $9''$, the joint therebetween by $10''$, the terminal axes of links $8''$ and $9''$ by $11''$ and $12''$ respectively, and the extended positions of these parts by the broken line figures.

55 In Figure 6, the axis $7''$ has motion in the plane indicated at "f" separated from the plane at "g", containing the terminal axis $6''$, by the distance "k" which is substantially equal to the difference in length of the links $1''$ and $2''$, in turn, of lengths approximately equal to "j" and "i" respectively.

60 Likewise, in Figure 7, the lengths of the links $8''$ and $9''$ are substantially of the lengths "d" and "c" respectively while the difference of length thereof is approximately equal to the distance "e" by which the planes at "a" and "b", containing the terminal axes $11''$ and $12''$, are separated.

70 The terminal axes $6''$ and $7''$ may thus be considered as having motion relatively in the planes "g" and "f" respectively, and the terminal axes $11''$ and $12''$ as having motion relatively in the planes "a" and "b".

75 The two link systems may, therefore, be composed of links of such complementary length as will be substantially equal to the distance be-

tween the planes containing the axes joining the separate links into pairs and the planes containing the terminal axes of the links when the machine is in the retracted position. Stated in another manner, the difference in length of the links in each pair is substantially equal to the distance of separation of the planes containing the terminal axes thereof and through which the latter may be said to move relatively. These proportions provide for the folding of the links into a very compact space approaching a plane normal to the direction of movement of the terminal axes.

80 The sawing machine in which this device has been embodied comprises a base casting 20 to 15 which the table bracket 21 is bolted with its supporting face 22 aligned with the horizontal, a revolving frame 23 rotatably mounted atop thereof by means of the clamping bolt and nut 24 with which it is secured in the desired position, two link systems as described mounted upon the revolving frame 23 and carrying a head assembly 20 25.

The link systems comprise a link 8 pivotally attached to the revolving frame 23 by a horizontal 25 shaft at 11 and pivotally attached by a second horizontal shaft at 10 to the second link 9 whose outermost end is attached by a third horizontal shaft at 12 to the head assembly 25 , and counterparts of these links and pivots mounted upon 30 vertical shafts in which the link 1 is pivotally attached to the revolving frame 23 by a vertical shaft at 6 and connected to the link 2 by a second vertical shaft at 5 , the outermost end of the link 2 being connected to the head assembly by 35 a third vertical shaft at 7 .

A direct-driven saw arbor 26 and motor therefor 27 are suitably mounted upon the head 4 to allow of adjustment about a horizontal axis and vertically to permit of cutting to a predetermined 40 depth and bevel with reference to the table supported upon the face 22 of the table bracket 21 . The hand wheel 28 is provided to facilitate this adjustment of depth of cut.

A reflecting spring 29 is mounted upon a rod 45 30 pivotally secured to the revolving frame 23 at 31 to engage the stop 32 pivotally mounted upon the link 2 so that the momentum of the machine in a forward stroke may be utilized to return the saw to its retracted position with a minimum of 50 effort and time.

Another valuable characteristic of this machine is that by virtue of the weight of the links 8 and 9 the saw tends to move backward; no other means is thus required to cause the retraction of 55 the saw from the work.

An auxiliary safety device is illustrated in Figure 5 and in Figure 4. The handle 33 is pivotally mounted to the motor housing at 34 and 35 and in its lateral aspect is formed as a bell crank with a 60 rearwardly extending lever 36 engaging the part 37 through suitable means to cause it to rotate upon its pivot at 38 and so cause the disengagement of its hooked portion 39 from a suitable engagement 40 formed on the revolving frame 23 . 65 The descent of the arm 36 by force of gravity causes the engagement of the hook with the revolving frame and thus secures the saw in its retracted position against accidental extension. 70

Electrical control apparatus for the motor is indicated at 41 and the flexible conduit serving the motor at 42 .

It will be apparent that the device is applicable to a great number of mechanical devices 75

among which might be mentioned the following: sawing machines such as the one described, metal planing and shaping machines, drilling machines, and any device or contrivance requiring an easy 5 working rigidly guided reciprocating movement.

Having described my invention what I claim is:

A sawing machine comprising, in combination, a base, a frame rotatably mounted upon said base, a tool head, two systems of links of several 10 lengths joined together respectively upon par-

allel axes opposite termini of which systems are connected to said rotatable frame and said tool head respectively upon rigidly related axes mutually inclined and disposed upon said rotatable frame and said tool head in planes parallel with the line of motion of said tool head and respectively separated by distances substantially equal to the difference in length of the links constituting each pair.

ARTHUR E. DE KONING.
